PINTLE LOCK

John Schlitz, Leavenworth, Kans., assignor of
one-half to Ida Wilhelm Brugger, Bronxville,
N. Y.

Application September 4, 1934, Serial No. 742,586

22 Claims. (Cl. 70—23)

The invention relates to locks and primarily to that type of devices generally known as combination locks, operatable with or without a key, the locking and unlocking of which is controlled by movable members, each of which is moved to a certain predetermined position to effect the locking and unlocking of the lock on a shackle which may be of any form or construction.

The first object of the invention is to provide a combination lock operatable through combination means composed in part of pin tumblers formed of a plurality of sections of different lengths, certain of said sections being provided with annular grooves and provided with extending means in said grooves, for example in the form of expanding rings for foiling any attempt to feel the breaking point between movable lock members in which the said pin tumblers rest aligned, and by said means effect a greater simplicity with most solid, most reliable, compact and pick proof construction of locks of a character adaptable to various versatile uses and purposes in which it may be applicable, and provide means whereby the combination possessor may instantly manipulate the combination means in the dark, as well as in the light with the aid of a simple adjustable coin shape combination key, which can be made or manipulated to form any desired combination and to keep the combination secret from any possible onlookers while the lock is opened. It is further possible for the possessor of the combination to open the lock in case the combination key is lost, forgotten, or in case of light unnecessary.

Further objects of the invention are to provide a lock formed to favor a required shape as self protection against being caved in and twisted from implantation and having a shackle engaging means which will allow the general body of the lock to be constructed smaller, of less parts and thereby more solid, more powerful more durable, more burglar proof, more inexpensive, more reliable and capable by the simplest means of providing possibly billions of various combination codes from which any one code may be chosen.

The invention secures a further object with the provision of means whereby the combination may be more readily changed or altered if desired.

With the above and other objects in view, my invention consists chiefly in a pin tumbler lock comprising a compact interlocking body formed of two members adapted for relative movements and speedy extraction of pin tumblers with provision of means to engage a shackle or bolt and

protect the shear line, pin tumblers having expanding means and pin tumblers with reduced ends extending to the outer surface of said body, and extends to consist of pin tumbler locks of the class varying in certain details of modification of construction and combination of means and parts thereof within the scope of the invention, substantially as herein further described, and pointed out in the claims.

The foregoing and other objects which will appear as the nature of the invention is better understood, may be accomplished by a construction, combination and arrangement of parts such as is disclosed by the drawings. The nature of the invention is such as to render it susceptible to various changes and modifications, and, therefore, I am not to be limited to the construction disclosed by the drawings; but I am entitled to all such changes therefrom as fall within the scope of my claims.

In the drawings:—

Figure 1 is a side elevation of my invention in connection with a shackle and flange;

Figure 2 is a central vertical sectional view on line 2—2 of Fig. 4;

Figure 3 is a central vertical sectional view on line 3—3 of Figure 1;

Figure 4 is a front elevation of the invention with the flange as shown on Figure 1;

Figure 5 is a sectional view on line 5—5 of 30 Figure 2;

Figure 6 is an elevation of the face of member 2 on line 5—5 Figure 2;

Figure 7 is an elevation of my invention in modified form without shackle;

Figure 8 is a central vertical sectional view of Figure 7;

Figure 9 is a central sectional view on line 9—9 Figure 7;

Figure 10 is a front view of Figure 7 but showing the lock in open position for receiving or releasing a shackle or bolt;

Figure 11 is a perspective exploded view of the lock of Figure 7 without duad cover rings;

Figure 12 is a perspective exploded view of the duad cover rings;

Figure 13 is an example showing the possible arrangement of pin tumblers with their shear line applicable to Figures 11 and 51;

Figure 14 is a perspective view of a center section of the pin tumbler with one ring removed;

Figure 15 is a perspective view of the jaw;

Figure 16 is a perspective of the member coupling key;

- Figure 65 is a top elevation of an adjustable combination key in further modified form, for example;
- Figure 66 is the reverse or dial face of the adjustable combination key of Figure 65 applicable to Figure 64;
- Figure 67 is a central vertical sectional view on line 67—67 Figure 65;
- Figure 68 shows a plurality of key points or adjustable members of the combination key of Figure 67;
- Figure 69 shows a plurality of pin tumblers having expanding members as shown in Figures 61, 60, 64;
- Figure 70 is a side elevation of my invention in a final major exemplary modified form;
- Figure 71 is a side elevation of Figure 70 with the bolt, bolt housing and lock implantation in section;
- Figure 72 is a central vertical section on line 72—72 of Figure 74 with the movable face member and closure member and a combination key in elevation;
- Figure 73 is a central vertical section on line 72—72 of Figure 74 with a vertical section of the combination key;
- Figure 74 is a front face elevation on line 74—74 of Figure 70 with the bolt in closed position;
- Figure 75 is a central sectional view on line 75—75 of Figure 72 with the bolt in closed position and the lock members moved for moving the bolt to opening position;
- Figure 76 shows an enlarged elevation of the 75

pin tumblers and expanding means as arranged in Figure 73;

Figure 76A is a sectional view of Figure 76;

Figure 77 is a central sectional view on line 5 75—75 Figure 72 but with the bolt drawn from closed position and the lock members moved to move the bolt;

Figure 78 is an elevation on line 78—78 Figure 10 70 with the lock implacement in section;

Figure 79 is a front elevation of the adjustable 10 master combination key;

Figure 79A is a side elevation of Figure 79;

Figure 80 is a perspective view of the bolt;

Figure 81 is a perspective view of the bolt cas- 15 ing;

Figure 82 is a combination key keeper with the cover of the fabric rolled back to reveal the combination key and combination code leaflets;

Figure 83 is a plan of the rear member of the 20 invention of Figure 70;

Figure 84 shows diagrammatically an adjustment of the tumblers corresponding to the setting of the key of Figure 79.

Figure 85 shows the tumblers of Figure 84 25 aligned in lock releasing position;

In the accompanying drawings, the number 1 indicates what is throughout to be generally named the face member, and 2 the rear member 30 of the lock which has pin tumbler sections 3—3'—4—5—6—7—8—8' with expanding pin tumbler members 9 in groove 9' in certain sections, whereby the tumblers may be aligned to 35 release face member 1 for movement to withdraw means 10 carried thereby from engagement with the shackle 11. The lock is opened by forcing a predetermined number of said pin tumblers together or separately to a predetermined depth to allow the opening and closing operation of the lock. Figures 1 to 6 show an arrangement of 40 pin tumblers as shown in Figure 13. The tumblers 4 or 7 for instance, are moved into disalignment by the rotary motion of the lock on the extending bulge 12 on the inner side of the cup shape shackle flange 13. After alignment of 45 pin tumblers shown in Figure 85 the face member 1 is moved to allow the release of the jaw 10 from the shackle 11. It is also shown that means may be provided in all forms to partly or wholly cover the line of contact of the shear line faces 50 of the face member and of the rear member as protection against attack, in that the extending means 15 and 15' are provided by the rear member 2 Fig. 5 and by the face member 1 Fig. 6, while like protective extending means are pro- 55 vided in Figures 7 to 12 by rings 16 and 16', and by a flange 13' in Figures 33 to 37, and by one flange 17 in Figures 39 to 48, by the general body of the lock in Figures 50 to 56, by the lock implacement in Figures 60 to 64 and by the inner flange 60 18 of the cylindrical form 19 of the rear member 2 in Figures 70 to 83. It is also understood that all forms throughout can be provided with coil springs 20 as shown in Figures 24 to 73. By the foregoing, it is seen that while the movable face 65 member 1 is held keyed to the rear member 2 by integral extensions 21 and 21' Figure 6, or by an insert 22 Figures 9 and 15 and the insert 22' Figure 16 corresponding to integral extensions 21 and 21' of Figure 6 a projection 10 for shackle 11 is provided in each instance. It can be seen that 70 the said means for connecting members 1 and 2 and locking the shackle are immovably mounted in a channel 23 of the face member 1 and mov- 75 ably held in the opposite channel 24 of the rear member 2 Figure 11 to hold or release a shackle

11 mountable within bores 25, 26 and 27 of lock members 28, 28' 2 and 1 Figures 1 to 48.

The rear member as exemplified in Figs. 38 to 49 and Figs. 70 to 83 is provided with a flange which at its outer end 17—18 is pressed inward 5 to be narrowed by a press upon a fixed smaller diameter of the face member and thus movably unite both members permanently together by the forming of a rim as the final act of a method of assembling.

It can be further seen that a screw 29 (Figs. 29 and 30) or a tumbler (Fig. 21) resting with its end portion in the elongated groove 29' not only limits the horizontal movement of the face member but also by withdrawal from said groove allows thereby the removal or readjustment of pin tumblers to provide a different combination.

Means 21, 21', 22, 22' key the face member and 20 rear member together in Figures 1 to 30, and allowing access to the pin tumblers by removal of the face member 1 from the rear member 2. The flange 17 Figures 38 to 48 and flange 18 of Figures 25 70 to 83 prevents such action but allows in place 25 access to the pin tumblers through a movable closure member 28 of the class for example shown in Figures 39 to 46, which is held movably mounted with key faces 39 against counter key faces 31 and held immovable by a movable shackle 11 30 with the bore 25. In place of a closure member 28' Figures 33 to 37, a closure member 32 (for the same purpose) is provided in Figures 70 to 78, wherein the combination is changeable by removal of the pin tumbler through the closure 35 after the removal of the screw 32' from the rotatable closure member 32. Access to tumblers in Figure 50 for like change of the combination is possible by the removal of both the screw 33 and the key pin 34, and in Figures 60 to 64 by the 40 removal of screws 35.

It can be seen in Figures 72 and 78 that the said closure member is rotatably mounted to allow the removal and replacement of spirally mounted 45 pin tumblers and relative springs through the hole at any place. In the lock of modified forms, as exemplified in Figures 39 to 85 inclusive the members 1 and 2 are locked to perform proper functions by rotary movement, and that the jaws 36 shown in Figures 39 to 45 have a projection 50 37 for movement in an oval groove 38 shown in Figures 39 to 45, the difference between the length and width of the oval (or a spiral) groove forces the jaws to move into and out of an annular elongated groove or other bolt engaging 55 means about a shackle. Rib 48 (Fig. 48) engages groove 37' of jaw 36 and in the rotation of face member 1 carrying with it the jaw causes the same to move either to locking or unlocking position by reason of the eccentric shape of the 60 rib. The rib is formed in a plate 41 mounted as shown in Figure 46. The locking and unlocking movement is provided in Figures 70 to 85 in a member 10' by a groove 44 Figure 72 for allowing the release and preventing the release of the bolt 65 or a shackle. The pin tumblers vary in length or sections throughout but serve to perform like functions and the sections as shown in Figure 76 can be shifted to provide any desired combination as exemplified in Figures 84 and 85.

Any number of locks of the class may be operated by placing key points 45, 46 and 47 Figure 68 of a predetermined combination upon the combination key 48, which may be provided with handle 49 having a point extractor 49' for aid- 75

ing the removal of key points from the combination key Figs. 67 and 79. It is to be understood that a combination key 50 Figures 31 and 32 can be of service in any pin tumbler lock in which the pin tumblers protrude from the surface of the dial face as the key of Fig. 31 being non-adjustable can be used only for locks having the same combination as that of the key. The combination key of Figure 32 is provided with holes 51 and an assortment of re-arrangeable sections 52 which fill partly or wholly the said holes to form a combination. The master key of Fig. 79 allows change of combination more quickly than the key of Figure 32 and may open a million locks 15 each lock of a different combination and may be conveniently carried by a means 53 Figure 82, which may carry with it for convenience a considerable number of paper dial leaves 54 having the combination and number of the lock stamped 20 on each leaf.

When the combination is set on the combination key as for example as shown in Figure 79, the key is pressed on the dial face 55 Figs. 72 and 73 to allow key points 45, 46 and 47 to force the 25 pin tumblers to alignment as in Fig. 85 to allow the turn of the combination key to rotate the face member 1 360 degrees and allow the pin tumblers to fall automatically again in disalignment with the shear line 14 as shown for example 30 in Figure 84. Rotation of face member 1 moves member 10' from one end of slot 70 to the other by means of spiral groove 48 thus placing said member 10' in position to contact the end wall of opening 58 in bolt 11' to thereby retract said bolt 35 upon the continued rotation of said face member, against the pressure of the bolt projecting spring. The spring will force the bolt to re-locking position limited by the extending pin 61 which meets the bolt casing 62 (Fig. 75). The bolt casing 40 (for example) fastened by screws 63, 63' and through holes 64, 64' Figure 81 and the casing has a side recess 65 to allow the latch point 66 of the latch 67 to be moved into to lock the lock from the inside and to prevent the lock from 45 being opened from the outside. It is to be understood that the bolt housing rests stationarily in the centrally located annular groove 68 on the rear member 2 to prevent the lock from being drawn from implacement 69 while the door is 50 locked. It is understood that the locking action of the latch 67 prevents the rotation of the lock and consequently prevents the lock from being opened from the outside.

The above described operation naturally forces 55 the extending member 10' to one side within the oblong hole 70 of the annular groove 68 Figure 71 and Figure 83, and the reverse operation of the lock will force the said member 10' to the other side or free area 57 of the bolt and thus 60 provide free rotation of the member 2 without moving the bolt, thus the lock is locked, and the application of a pipe-wrench to twist the lock open would only rotate the lock freely. Having thus described the lock of this class, I point to 65 Figures 50 to 64 inclusive to show that I do not desire to limit myself to exact details of construction and that I am aware that a lock of this class may be reduced to a more simple form for certain purposes as shown for example in Figure 70 50 in which twin major parts possess the general form of a lock of the class in that two members 71 and 71' form the combined interlocking jaws 72 and housing for tumblers of the class shown in Figures 13, 18, 58 or 68. The lock of Figure 60 75 with tumblers of the class Figure 13 can be op-

erated with or without the use of combination key. Pin tumblers may also be provided with expanding rings 9 to foil the attempt to pick the lock. The members 71 and 71' are held together by a screw 33 passing through the hole 73 5 of member 71' into screw threads 74 of member 71 and said screw is locked therein by a key pin 34 (Fig. 57) passing through a hole 75 of member 71 and into the said screw to prevent the screw from being removed while the section 76 in closed 10 position covers the pin to prevent removal of the same while the lock is locked.

It may be shown in Figures 60 to 64 that the lock of the class can be applied to a door A or door frame B or vice versa, in that a face member 1 is fastened into the door A (Fig. 60) for example within a rim 77 followed by the rear member 2 screwed, riveted or welded to a door A. The rotation of member 1 moves a bolt 78 into and out of a recess 79 in the door frame B. The 20 rotating face member 1 having a threaded hole 80 to receive threads 81 of the bolt 78 moves the slidably mounted bolt 78 into the stationary rear member 2. The bolt 78 has flat side to prevent the bolt from turning. It is immaterial 25 whether the threaded end of the bolt 78 is in the non-movable rear member and the slideable flat sided end of the bolt in the rotatable member, the movement in and out of the recess 79 would be the same. It is to be further understood 30 that the end of the annular groove 3' of tumblers 3 may be flush with the face of the face member throughout from Figure 1 to Figure 74 inclusive, as shown in Figure 84. The adjustable combination key Figure 79 is also operable in 35 Figures 1 to 70 inclusive with allowance for minor changes in the length, location and number of tumblers in each lock. The adjustable key points 45, 46 and 47 fit the face of each lock. Tumblers 40 may also protrude from the face of locks from Figure 60 to Figure 74 as in Figures 1 to 54, making adjustable combination key Figure 79 therefore also useable throughout in that the members 45, 46 and 47 Figure 68 may possess inward extending holes of the depth as of the length of 45 key points 45', 46' and 47'. It is evident that both the spiral arrangement of pin tumbler holes 43 (Figs. 70 to 79) and the circular arranged holes are applicable throughout. And that the combination key 48 Figure 79 has pins 82 to engage holes 83 Figure 74 to set the key 48 in line with grooves 84 and 85 Fig. 74. The key may have instead a groove or rib 86 Figure 65 as in Figure 67 to join a counter groove or rib on any lock as exemplified in 84 Figure 64. The key may have 55 instead a point 87 within a hole 88 (Figure 43) to fit into a recess 89 on the extension 90 (Figs. 38 to 46), or a key Figure 32 may have a bar 91 across a hole 92 as in Figure 31 to enter a groove 93 Figure 24, or key Figure 31 may have a point 94 as Figure 32 on its outer rim to fit into a recess 95 of a rim 96 as exemplified in Figs. 28 and 36. The key may be adapted by these minor changes to all locks of the class herein described.

Therefore, it can be seen by the foregoing that I have provided several specific, reliable compact locks and keys capable of fulfilling in each instance the use and purpose peculiar thereto within the general spirit of the invention which broadly aims to secure a lock practically pick proof by the employment of sectional tumblers around certain sections of which are placed expandable spring rings to aid in disguising the shear line. These tumblers are adaptable to the various locks disclosed and do not interfere with the construc- 75

tion permitting free rotation to prevent twisting apart of the lock.

While I have herein shown and particularly described the embodiments of my invention for 5 said various uses by arrangements and re-arrangements of related parts for providing the same leading aim within the spirit of my invention I do not wish to be understood as limiting myself to the precise details of construction 10 shown as further like changes can be readily made without departing from the spirit of my invention.

What I claim is:

1. In an adjustable lock, a rear member provided with a plurality of pin tumbler openings, a face member movably mounted against the said rear member provided with a plurality of pin tumbler openings through the said face member in alignment with the pin tumbler openings in 20 said rear member, expandable sleeves, pin tumblers having annular grooves with said expandable rings therein, and an adjustable means allowing the removal of said pin tumblers movably held in each of said pin tumbler openings for 25 allowing and preventing the movement of the said movable face member against the said rear member and to allow and prevent the movable face member from providing a clamping act upon a shackle.

2. In an adjustable lock, the combination of a rear member provided with a plurality of pin tumbler openings, a movable face member movably mounted against the said rear member provided with a plurality of pin tumbler openings in 35 alignment with pin tumbler openings of said rear member, expandable sleeves, a plurality of pin tumblers provided with said sleeves and movably mounted in each of said pin tumbler openings, coil springs, and adjustable means to allow 40 the removal and prevent the removal of the said pin tumblers with the said coil springs, clamping provisions, and means to allow and prevent a clamping purchase upon a shackle.

3. In a lock, the combination of elements movably engaging each other and provided with pin tumbler openings, a plurality of re-arrangeable alignable pin tumblers of various sectional lengths in each of said openings, annular grooves provided on several of said pin tumblers, the 50 said pin tumblers of said various sectional lengths reduced in diameter to fill in the said openings of reduced diameter spaced from the end of the tumbler openings to prevent removal thereof through outer openings in which the reduced ends move as buttons for operation manually and by a key, expandable spring rings about said tumblers having annular grooves to rest said spring rings therein.

4. In a lock of the class described, a pair of lock members with their inner faces snugly mounted against each other and provided with dual aligned pin tumbler openings, protecting overlapping extending means provided to the 65 outer sides of said lock members to protect the said joining faces, a series of alignable pin tumblers in each of said aligned pin tumbler openings, a shackle release means provided on a said lock member to allow and prevent the release, and 70 means to move the said pin tumblers to disalignment to prevent the movement of the said faces of the said lock members, said pin tumblers with reduced extending sections to move the said pin tumblers to alignment to allow the disalignment 75 of the said dual openings to move the said

shackle release means with a said lock member to unlock the lock.

5. In a lock comprising members provided with a plurality of pin tumbler openings, a movable set of pin tumblers, each of said tumblers of separate predetermined length selectively predeterminedly arranged in each of said pin tumbler openings, expanding means about the sections of said inner located tumblers which are of reduced diameter to prevent play of said tumblers 10 against the side walls of said openings and prevent picking of the lock.

6. A lock having its face member provided with a series of pin tumbler openings, pin tumblers provided with an annular shoulder to prevent 15 the outward escape of pin tumblers through the face of the face member, movable inner pin tumblers, each of said tumblers of predetermined length to allow predetermined arrangement and re-arrangement of said pin tumblers in each of 20 said pin tumbler openings, expanding means about a plurality of said inner pin tumblers, rear members, a part of said pin tumblers extending into a said rear member, and means to allow 25 proper alignment of said pin tumblers to allow the lock to open.

7. A lock of the class comprising a solid body formed of two members movably mounted against each other and provided with a plurality of alignable pin tumbler openings therein, a movable bolt engaging means between said two members, 30 adjustable pin tumblers movably mounted in said openings and through said bolt engaging means to allow the releasing movement of the said bolt engaging means to release the lock from 35 a bolt.

8. A pin tumbler lock having a dual body of a face member and a rear member movably mounted to each other and provided with a plurality of alignable pin tumbler openings therein, 40 adjustable pin tumblers movably mounted in said openings, a movable bolt engaging means provided on one of said members.

9. A pin tumbler lock having a dual body of a face member and rear member movably mounted to each other and provided with a plurality of alignable pin tumbler openings therein, adjustable pin tumblers movably mounted in said openings, a means on said rear member to allow 45 the removal of the face member from the said rear member at a predetermined point of movement when the said tumblers are aligned, a lock engaging means between said face and rear members, and a means to align said tumblers to move said face member to engage said lock engaging 50 means.

10. A pin tumbler lock having a dual body of a face member and a rear member movably mounted to each other and against each other and provided with a plurality of alignable pin tumbler openings therein, adjustable pin tumblers movably mounted in said openings, a means on said rear member to allow 60 the removal of the face member from the said rear member at a predetermined arranged point when the said tumblers are aligned.

11. In a lock, the combination of elements movably mounted against each other provided with alignable pin tumbler openings, a plurality of rearrangeable alignable pin tumblers of different lengths in each of said openings, the said pin tumblers in several sections reduced in diameter to fill in the openings of reduced diameter spaced from the outer manually manipulatable push button end of the said tumblers to prevent 75

- removal thereof through outer openings from said tumbler openings in which the reduced push button ends move for operation manually and by a key, and expandable spring rings about said 5 tumblers having annular grooves.
12. In a lock of the class described comprising dual solid elements directly joining each other, said elements provided with dual pin tumbler openings, said elements provided with inner 10 surfaces facing each other directly in alignment with said dual pin tumbler openings, adjustable pin tumblers, movably mounted in each of said openings, a said element provided with a cam groove at a said inner surface, locking means 15 provided with provisions of means movably resting in said cam groove, a said element provided with a vertical groove opposite of said cam groove to allow the said locking means to move therein to allow the release and prevent the release from 20 a shackle.
13. A lock of the class described comprising a substantial solid body formed of two members adapted for relative movement, said members provided with a plurality of alignable pin tumbler openings, pin tumblers in said openings to 25 releasably hold the members locked and tumblers extending to the outer face of said body to serve as push buttons at one end thereof, a shackle engaging means whereby relative movement of 30 said members will provide release engagement from a shackle.
14. In a rotatable pin tumbler lock of the class described comprising a substantial solid body formed of two members adapted for relative 35 movement and speedy extraction of tumblers and being provided with a shear line guard and with a shackle engaging means, said members provided with a plurality of alignable pin tumbler openings pin tumblers in said openings to 40 releasably hold the members locked and tumblers extending to the outer face surface of said body to serve as push buttons at one end thereof to provide alignment of said tumblers to allow release engagement of said shackle engaging means 45 from a shackle.
15. A lock of the class described comprising a substantial solid body formed of two members adapted for relative movement, said members provided with a plurality of alignable pin tumbler openings, a plurality of pin tumblers in said 50 openings to releasably hold the members locked, said tumblers in several sections of different lengths and reduced in diameter to fit in the said tumbler openings of reduced diameter spaced from the end to the tumblers to prevent removal 55 thereof through outer openings from said tumbler openings in which the reduced ends move as push buttons for operation both manually and by a key.
16. A lock of the class described comprising a substantial solid body formed of two members adapted for relative movement and being provided with a shear line protecting means, said members provided with a plurality of alignable pin tumbler openings, a plurality of pin tumblers in said 60 openings to releasably hold the members locked, said tumblers in several sections of dif-

ferent lengths and reduced in diameter to fill in the said tumbler openings of reduced diameter spaced from the end to the tumblers to prevent removal thereof through outer openings from said tumbler openings in which the reduced ends move as push buttons for operation both manually and by a key. 5

17. In a locking device, the combination of a lock with a shackle, a flange provided with a cup formed side wall to cover a section of the lock 10 and the shackle from attack substantially as described.

18. In a lock of the class described comprising a body formed of two members adapted for relative movements and provided with a spiral track, 15 said members provided with a plurality of alignable pin tumbler openings, sectional pin tumblers in said openings to releasably hold the members locked and around certain sections of which are placed expandable spring rings to aid in disguising the shear line, and engaging means including said track whereby relative movement of 20 said members will move said engaging means to engage a shackle.

19. In a lock of the class described comprising a body formed of two members adapted for relative movement and provided with a series of spirally located pin tumbler openings, pin tumblers in said openings to releasably hold the members locked. 25

20. In a lock of the class described comprising a body formed of two members adapted for relative movement, said members having a plurality of alignable pin tumbler openings, pin tumblers in said openings to releasably hold the members locked, a plate provided with an oval cam track carried by said members, shackle engaging means, a shackle, and means including said track whereby relative movement of said members will move 35 said engaging means to release said shackle. 40

21. In a pin tumbler lock of the class described comprising a substantial solid body formed of two members adapted for relative movement and speedy extraction of tumblers and provided with a shear line guard and with a shackle engaging means, said members provided with a plurality of alignable pin tumbler openings, a plurality of pin tumblers in said openings to releasably hold the two members locked, said tumblers in several sections of different lengths and reduced in diameter to fill in the said tumbler openings of reduced diameter spaced from the end to the tumblers to the surface of said body to prevent removal thereof through outer opening from said tumbler openings in which the reduced ends move as a push button for operation of said tumblers both manually and by a key to effect release engagement of the lock. 50 55

22. In a lock, the combination of elements movably grasping each other and provided with pin tumbler openings, a plurality of re-arrangeable alignable pin tumblers of various sectional lengths in each of said openings, annular grooves provided on several of said pin tumblers, expandable spring rings about said tumblers having annular 60 grooves to rest said spring rings therein. 65

JOHN SCHLITZ.
